US00D953889S

(12) **United States Design Patent** (10) **Patent No.:** **US D953,889 S**
(45) **Date of Patent:** **** Jun. 7, 2022**

(54) **CONTAINER**

- (71) Applicant: **PepsiCo, Inc.**, Purchase, NY (US)
(72) Inventors: **Martin Eduardo Broen**, New York, NY (US); **Christopher Erlin Granneberg**, Los Angeles, CA (US); **Klaus Rosburg**, Brooklyn, NY (US)
(73) Assignee: **PepsiCo, Inc.**, Purchase, NY (US)
(**) Term: **15 Years**
(21) Appl. No.: **29/736,395**
(22) Filed: **May 29, 2020**

Related U.S. Application Data

- (63) Continuation of application No. 29/609,310, filed on Jun. 29, 2017, now abandoned.
(51) **LOC (13) Cl.** **09-01**
